FRANK J. HUETTEMAN, ANTHONY F. CRAMER, FRANK A. SCHAUML, AND HENRY C. WIEDEMAN, OF DETROIT, MICHIGAN, ASSIGNEES, BY MESNE ASSIGNMENTS, TO THE GLASS ENAMELED PACKAGE COMPANY, OF DETROIT, MICHIGAN, A CORPORATION OF NEW YORK.

KEG OR CASK.

1,086,826.

Specification of Letters Patent.

Patented Feb. 10, 1914.

Application filed April 1, 1912. Serial No. 687,906.

To all whom it may concern:

Be it known that we, FRANK J. HUETTEMAN, ANTHONY F. CRAMER, FRANK A. SCHAUML, and HENRY C. WIEDEMAN, citizens 5 of the United States, residing at Detroit, county of Wayne, State of Michigan, have invented a certain new and useful Improvement 10 in Kegs or Casks, and declare the following to be a full, clear, and exact description of the same, such as will enable others skilled in the art to which it pertains to make and use the same, reference being had to the accompanying drawings, which form a part of this specification.

15 This invention relates to kegs, half-barrels, whole barrels or casks and is especially adapted for kegs, packages or casks to hold beer or liquors.

It has for its object a cask constructed of 20 staves of a compressed filler material such as cork or other material that is adapted to act as a heat insulating medium. These insulating staves are adapted to be arranged about a metallic inner receptacle that is 25 enameled on its inside. Each insulating stave is provided with a stave-sheath of metal. These stave-sheaths fit into grooves left in the staves and are forced together by the application of the hoops of the cask.

30 This affords a structure which keeps the liquor or beer cool and which is properly reinforced so as to make a very strong cask.

In the drawings:—Figure 1, is a longitudinal section of the cask. Fig. 2, is a cross 35 section of the cask. Fig. 3, is a detail perspective of one of the metallic stave-sheaths. Fig. 4, is a detail perspective of one end of one of the staves.

1, is a stave shaped quite similarly to the 40 ordinary stave of a wooden cask. This stave is preferably made of ground cork that is pressed into the shape of a stave. However, almost any other filler material may be used that can be compressed into stave shape. On each side of the stave is cut away a groove as at 2, while the ends of the stave on the inside are grooved as at 3 to receive the head of the cask. These staves are arranged about an inner metallic receptacle 4 that we prefer to enamel on the inside, so as to keep it clean and sweet. The stave-sheaths 5 are adapted to fit one over each

stave 1, they being provided with inturned edges 6. These inturned edges are narrowest at the center of the cask, as shown 55 by the dotted lines in Fig. 1 and are of about uniform width from the center to a point adjacent the ends of the inner receptacle 4, where they enlarge in width to the width of the stave. This is done in order 60 that the metallic edges may not contact the inner receptacle and injure it, while at the ends, the stave-sheaths help to keep on the head 7 of the cask. For this purpose the sheath is notched as at 8 and into this notch 65 the head 7 is adapted to fit. The staves 1 are cut away or grooved as at 2 to receive the inturned edges 6 of the stave-sheaths, the groove 2 conforming in depth to the width 70 of the stave-sheaths at different points along 70 its length. When all of the stave-sheaths have been fitted over the insulating staves by dropping the turned in edges 6 of the sheaths into the cut away portions of the staves, the hoops 9 are forced over the stave-sheaths and tend to force the stave-sheaths 75 tightly together and into tight relation with the staves. At each end of the cask, the staves would be left unprotected as the sheaths are open at their ends. To shield 80 the ends of the staves and reinforce the ends of the cask, we employ a reinforcing ring 10 at each end, this reinforcing ring 10 comprising a circular strip of U-shape in cross section, which fits over the top of the as- 85 sembled staves and stave sheaths. It also fits over the top of the metallic sheathing 11, which is used to cover the heads 7 and which is folded up at the edge as at 12 so that it lies folded under the reinforcing ring 10. 90 The heads 7 are made of a similar material to the stave and are protected on their insides by resting directly on the ends of the inner receptacle 4 and are guarded on the outside by the sheathing 11. The sheathing 95 11, at one end of the cask, is, with the head 7, drawn tightly to the inner receptacle by the tap 13, which is made the subject of a separate application. The usual bung hole and bung 14 is provided in the bilge of the cask. 100 From the foregoing description, it is seen that our cask is constructed of cork or any other heat insulating material and that by reason of the metal sheaths and reinforcing

2
rings for the ends, that it is of great strength and durability and withal simple in construction and readily assembled.

What we claim is:—

- 5 1. A cask, having in combination, a plurality of staves grooved at their ends, a stave-sheath for each stave provided with inturned edges notched at the ends in registry with the grooves of the staves, a head 10 adapted to fit in the groove and notch, a sheathing adapted to engage on the outside of the head and having turned up edges and a reinforcing ring adapted to fit over the staves and stave-sheaths engaging over the 15 turned up edges of the head sheathing, substantially as described.
- 20 2. A cask, having in combination, an inner receptacle, a plurality of staves, a stave-sheath for each stave provided with turned-in edges of less depth adjacent the 25 inner receptacle than the thickness of the staves, the said stave sheath edges widening at the ends and heads for said cask adapted to be held in by the widened portions 30 of the turned-in edges of the stave-sheaths, substantially as described.
- 30 3. A cask, having in combination, an inner receptacle or container, a plurality of staves constructed of soft heat-insulating material and arranged edge to edge about the inner 35 receptacle to pack the same, the edges of the staves being cut away on the exterior side, a plurality of stave-sheaths comprising metal strips with turned-in edges that are 40 adapted to fit into the cut-away portions of the staves to form in the aggregate a complete metallic casing for the staves, suitable insulated heads engaging over the heads of the inner receptacle and means for forcing the stave-sheaths together to thereby 45 press the same into intimate relation with the staves and the staves into intimate relation with the container, substantially as described.
- 45 4. A cask, having in combination, an inner receptacle or container, a plurality of staves constructed of a soft heat-insulating filler material that is pressed into stave shape and arranged edge to edge about the inner 50 receptacle to pack the same, the edges of the staves being cut away on the exterior sides, a plurality of stave-sheaths comprising metal strips, one to cover each stave and having turned-in edges that are adapted 55 to fit into the cut-away portions of the staves to form in the aggregate a complete metallic casing for the staves, suitable insulated

heads fitting the stave structure and engaging over the heads of the inner receptacle and hoops adapted to be forced over the 60 stave-sheaths for forcing the stave-sheaths together and into intimate relation with the heat-insulating filler material and for forcing the heat-insulating filler material against the container, substantially as described. 65

5. In a cask, the combination of a container, soft filler material packed about the sides of the container, a sheathing structure made up of a plurality of staves of sheet metal that fit together at their sides when 70 the hoops are applied and hoops for forcing the staves of the sheathing together to secure them in edge to edge relation and to pack the filler material into intimate relation with the container, substantially as described. 75

6. In a cask, the combination of a bilged container, filler material about the container, and a bilged sheathing structure comprising a plurality of sheet metal staves and means for forcing the staves together to compress 80 the filler material about the container, substantially as described.

7. In a cask, the combination of a bilged container, heat-insulating filler material about the container, and a bilged sheathing 85 structure comprising a plurality of sheet metal staves having turned-over edges, the said turned-over edges of adjacent staves engaging with each other, and hoops for compressing the bilged sheathing whereby 90 the filler material is compressed upon the container, substantially as described.

8. In a cask, the combination of a container, a plurality of staves constructed of yieldable heat-insulating material, and a 95 sheathing structure comprising a plurality of sheet-metal stave sheaths formed of strips of sheet metal turned over at the sides so as to cover the outside of each stave and extend partially over each side, a stave-sheath fitting over each stave of yieldable insulating material, and means for forcing the stave-sheaths together to compress the yieldable insulating material upon the container, substantially as described. 100 105

In testimony whereof, we, sign this specification in the presence of two witnesses.
